FISHING HOOK DISLODGER

Arthur C. Hargus, 7405 Gayola, St. Louis, Mo.

Filed Oct. 10, 1961, Ser. No. 67,033

Term of patent 14 years

(Cl. D31—4)

FIG. 1

FIG. 2

FIG. 3

FIG. 4

FIG. 1 is a side elevational view of a fishing hook dislodger, showing my new design;

FIG. 2 is a side elevational view of the opposite side thereof;

FIG. 3 is a top plan view thereof; and

FIG. 4 is a bottom plan view thereof.

I claim:

The ornamental design for a fishing hook dislodger, as shown.
